UNITED STATES PATENT OFFICE.

HARRIE A. BALLARD, OF BOSTON, MASSACHUSETTS, ASSIGNOR TO THE BOYLSTON MANUFACTURING COMPANY, OF SOUTH BOSTON, MASSACHUSETTS, A CORPORATION OF NEW JERSEY.

TREEING-STAND.

1,087,423.

Specification of Letters Patent. Patented Feb. 17, 1914.

Application filed September 29, 1908. Serial No. 455,333.

To all whom it may concern:

Be it known that I, HARRIE A. BALLARD, of Boston, in the county of Suffolk and State of Massachusetts, have invented certain new and useful Improvements in Treeing-Stands, of which the following is a specification.

This invention relates to treeing stands used in the process of manufacturing shoes, and consists of various improvements in the arrangements and construction of a treeing stand whereby the operation and efficiency thereof is enhanced.

Referring to the accompanying drawings, Figure 1 represents a top plan view of a treeing stand with a plurality of trees mounted thereon. Fig. 2 represents an elevation thereof partially in section. Fig. 3 represents a section on line 3—3 of Fig. 2. Fig. 4 represents a vertical section in a plane transverse to that of Fig. 2. Figs. 5 and 6 represent sections on lines 5—5 and 6—6 of Fig. 4.

The same reference characters indicate the same parts in all the figures.

Referring to the drawings, which represent one embodiment of the invention, to the details of construction of which I am not limited, a treeing stand is illustrated as having the hollow column or standard 20 with the flaring base 21. To this column is adjustably secured a table 22, said table being attached to a sleeve 23 having a threaded connection with the column or standard 20 and held against rotation after adjustment by a set-screw 24, adapted to take into a groove 25 in said column, as shown in Figs. 4 and 6.

Rotatively mounted upon the upper portion of the column or standard, and supported by the sleeve 23, so as to be adjustable therewith, is a turret indicated as a whole at 26 and having radial and upwardly projecting arms 27, of which there may be as many as desired. The turret is held against upward movement by a sleeve 28 rigidly and adjustably secured to the column or standard by a set-screw 29, taking into the groove therein, as illustrated in Fig. 4. The said turret is adapted to be rotated by hand to bring the shoes which are supported upon the arms 27 successively into operative relation to a treeing or ironing machine, located conveniently with respect to the stand.

The turret is adapted to be locked in as many different positions as there are trees or arms supporting them, and to this end the said turret is provided with locking notches 30, located in its periphery near its base, and adapted to be successively engaged by a latch 31 pivoted at 32 in the sleeve 23 and extending through an aperture in the flaring portion of the sleeve, as shown in Fig. 2.

The lower end of the latch is curved inwardly, so as to extend into the interior of the standard or column 20 and has connected to it a spring 33, the end of which is attached to the standard, as shown in Fig. 2, so as to yieldingly maintain the upper free end of the latch in locking engagement with one of the notches 30 or to cause it to engage one of said notches when permitted by the registration of a notch therewith. The lower end of the latch bears against a foot lever or treadle 34 which is pivoted at 35 to the base and extends outward through an aperture therein, as illustrated in Fig. 4. The pivotal connection of the lever with the base is of such a nature that the said lever may swing laterally as indicated in Fig. 5, the extent of its movement being limited by the width of the slot 36 in the base of the standard 20 through which the lever extends. The said lever is normally held at its upward extreme of movement by a helical spring 37 attached thereto and to a projection on the standard. This lever serves the function of expanding the trees as well as moving the latch 31 against the tension of the spring 33 to release the turret and permit it to be rotated one step.

For the purpose of expanding the trees, there is connected to the lever 34 an adjustable rod 38, which is located within the hollow standard and which is connected at its upper end with the substantially horizontal arm 39 of a bell-crank lever indicated as a whole at 40. This said lever is fulcrumed upon a stud 41 passed through two parallel lugs 42 projecting from the sleeve 28 between which the bell-crank is adapted to move and which hold said bell-crank against lateral movement. The arm 39 of the bell-crank extends into the interior of the standard through an elongated slot formed therein as shown in Fig. 4. The upright arm 43 of the bell-crank is formed at its upper end with a socket or recess 44, having a narrow

throat 45, through which the ends of the leg spindles are adapted to pass laterally as illustrated in Figs. 1 and 4.

The bell-crank is so located with reference to the locking notches in the turret that at the end of each partial rotation of the turret, one of the spindles is in operative engagement with the bell-crank so that by the depression of the arm 39, the bell-crank may be swung about its fulcrum 41 and the spindle moved longitudinally. The upper part of each of the arms 27 of the turret 26 forms a bearing, the axis of which is horizontal and radial to the axis of rotation of the turret, said bearings being indicated at 45^a. In each of said bearings is journaled a cylindrical end 46 of a tree-leg, each end having a groove 47 with which the end of the screw 48 may be engaged for holding the tree-leg against longitudinal movement and at the same time permitting it to rotate freely. Each of the trees is formed with a leg 49 and a foot 50, as shown in Fig. 2. The leg portion of the tree will first be described, and then the foot portion which is detachable to form the last or follower.

Referring now to Fig. 4, the leg is preferably formed of cast-metal and is hollow, as shown. It is provided with the adjustable back 51, having a pivotal, or ball and socket connection as at 52 with the leg near the outer end thereof. The inner or movable end of the back is provided with a head 53, located in the socket 54 in a block 55. A spring 56 is located in the socket and bears against the end of the back so as to hold its spherical end in the supplemental socket 52. Attached to the block 55, there is a screw 57 with which is operatively engaged a nut 58, 40 taking bearing against the rear portion of the leg and held in place by a gib 59 and screw 60. By rotating the nut 58, the block 55 and therefore the back 51, may be adjusted with relation to the leg so as to expand or contract the latter in lines from front to rear. The end of the leg is flat so as to receive a foot or last. In a slideway afforded by the front wall 61 of the leg and a rib 62, located in the leg, there is a slide 63 which is adapted to move in the direction of its length at an inclination to the longitudinal median line of the leg, the angle being comparatively sharp for a purpose to be described. For moving said slide, a spindle 64 is passed through an aperture in the rear end of the leg and is provided on its end with a hook 66 to engage a lug or projection 67 on said slide. The end of the spindle which projects beyond the cylindrical end 46 of the leg is provided with a head 65 which may consist of a nut in threaded engagement with said spindle and adapted to be held in place by a small screw 68. It is this head 65 that is adapted to enter the socket 44 in 65 the end of the arm 43 of the bell-crank on the

treeing stand. A compression-spring 69 is coiled upon the spindle, one end bearing against the end of the tree and the other bearing against a shoulder or collar 70 on the spindle. When the bell crank arm 43 is swung away from the end of the tree-leg, the spindle moves the slide to the position shown at the right of Fig. 4, at which place it may be locked by a device now to be described. The slide 63 is provided with a handle 71, projecting through a slot 72 in the wall of the leg, and to this handle is pivoted a cam or eccentric lock 73 having a handle 74 between which and the handle 71 is interposed a compression spring 75. The spring 75 tends to throw the cam-lock about its pivot 76 and engage it with the front wall of the leg, so as to hold the slide in any position to which it may be moved. To release said slide and permit its moving toward the foot portion, the operative grasps the handle 71 with the fingers and the handle 74 with the thumb of his hand, and forces them together to disengage the cam-lock from the wall of the leg. The leg is provided with the movable last-supporting spindle 77, which is pivoted at its inner end as at 78, and which is adapted to play back and forth between the rib 62 and the back of the leg. The said spindle has a shoulder 78^a flush with the flat end of the leg, and with a pin 79 projecting beyond said shoulder to receive the heel-portion 81 of the foot.

Having thus explained the nature of the invention and described a way of constructing and using the same, although without attempting to set forth all of the forms in which it may be made, or all of the modes of its use, I declare that what I claim is:

1. A treeing stand comprising a standard, a revoluble turret, a laterally swinging lever for locking said turret in pre-determined positions, and a plurality of expandable trees on said turret each having means including an operating member for expanding said tree, a separate lock for each said means, and means common to each said expanding means for actuating the same.

2. A treeing stand comprising a plurality of expandable trees each having means including an operating member for expanding said trees, and a separate manually releasable lock carried by said operating member for each said means, the said lock coacting with the wall of the leg of the tree.

3. A treeing stand comprising a standard, a turret, trees on said turret, a lock for the turret, and a lever for causing the expansion of the trees, said lever having a lateral movement for co-operating with the lock.

4. A treeing stand comprising a standard, a turret, expandable trees on the turret, a manually operative lever adapted to universal movement, tree expanding means operable by the lever when the latter is moved

in one plane, and turret locking means operable by said lever when the latter is moved in a transverse plane.

5. A treeing stand comprising a standard, a turret, trees on said turret, means for adjusting the turret longitudinally of the standard, the said means comprising an adjustable sleeve on said standard, and means consisting of a sleeve on said standard for preventing upward movement of said turret on said standard.

6. A treeing stand comprising a standard, a turret having vertical adjustment on said standard, a plurality of trees on said turret each having means for expanding the same, a member for actuating the said means in each of said trees in succession as the said turret is rotated, the said member being vertically adjustable independently of said turret, and means for actuating said member.

7. A treeing stand comprising a standard, a turret, trees on said turret, a table, means for simultaneously adjusting said table and turret longitudinally of the standard, the said table and turret being supported on said means, and adjustable means on said standard for preventing upward movement of said table and turret.

8. A treeing stand comprising a standard, a turret, a plurality of expansible trees on said turret each having means including an operating member for expanding said tree, and a member adjustably supported on said

standard which member is adapted to be engaged successively by the operating members in said trees whereby said operating members may be actuated, and a separate lock associated with each tree for locking the said operating member.

9. A treeing stand comprising a standard, a turret vertically adjustable on said standard, a plurality of trees on said turret, each having expanding means, a member adapted to actuate the said means in each of said trees in succession as the turret is rotated, the said member being supported upon the said standard and being adjustable thereon independently of the said turret, and means for actuating said member.

10. A treeing stand comprising a standard, a rotatable turret, a plurality of trees on said turret each having mechanism for expanding the same, a treadle, a lever connected to said treadle, and means for supporting the said lever above the said turret and within the circular path of travel of the said trees, the said lever having provision for engaging the said expanding mechanism in succession as the turret is rotated with a step-by-step movement.

In testimony whereof I have affixed my signature, in presence of two witnesses.
